BOTTLE BRUSH SPINDLE

Frank E. Fowler, Athens, Ga.

Application November 21, 1939, Serial No. 305,553

3 Claims. (Cl. 15—59)

This invention relates to improvements in bottle cleaning machines, especially those of the type including a brush carried on a live spindle positioned during the cleaning operation within the bottle.

In many instances during bottling under pressure of materials such as carbonated beverages or after bottling the bottle cracks and, because of the relatively high internal pressure, the pieces of the bottle move with high velocity causing serious damage and injury. Experience indicates that many of these accidents are traceable to small scratches on the necks of the bottles which serve to alter internal strains in the glass and to promote cracking of the glass with consequent shattering of the bottle due to pressure, especially if the bottle is roughly handled or struck in the vicinity of the scratches. These scratches, particularly those inside the bottle neck, frequently are caused during the cleaning of the bottles by particles of grit or other material ground between the rotating brush spindle and the bottle neck.

It is an object of the present invention to provide means whereby possibility of scratching the inside of bottle necks during cleaning as mentioned is substantially minimized.

Another object of this invention is to provide a sheath member around the brush spindle serving to protect the adjoining objects from contact with the spindle during rotation.

An advantage of the novel bottle cleaning device according to the present invention over other types of cleaning devices now currently in use is that whipping of the brush spindle is minimized, thereby increasing the useful life of brushes used in the machine to an extent markedly appreciable when compared with the life of brushes used in other machines.

Features of the device according to the present invention include its simplicity and ruggedness of construction, the former of which suits the device to manufacture under conditions of mass production and the latter of which assures long life for the device in use.

Other objects, advantages and features of a novel device according to this invention will be apparent to those skilled in the art during the course of the following description.

Regarded in certain of its broader aspects the present invention comprises, in combination with a brush carried on a live spindle, means for minimizing scratching of the bottle neck during cleaning which comprises a non-rotary sheath around the spindle.

In order to facilitate a more fully complete understanding of the matter of this invention, a specific embodiment thereof, herein illustrated, will now be described, it being clearly understood however that the illustrated embodiment is provided by way of example, not by way of limitation upon the present invention, and should be so construed when reading the subjoined claims.

- 10 Referring then to the drawings, Figure 1 is substantially a front elevational view of parts of a device for cleaning bottles, embodying features according to the present invention, Fig. 2 is a horizontal sectional view of Fig. 1, taken on the line 2—2, Fig. 3 is substantially a vertical sectional view of one of the cleaning units, Fig. 4 is a side elevation, partially in section of parts of the device illustrated in Fig. 1, showing the cleaning unit as in use, and Fig. 5 is substantially a horizontal sectional view of Fig. 3, taken along the line 5—5.
- 15 In describing the preferred embodiment of this invention, reference is made particularly to Fig. 1 wherein it will be noted that a bottle cleaning device, generally designated by the reference numeral 10 and comprising a frame 11 wherein is mounted a fluid tight gear box 12, is provided with a drive shaft 13 carrying a plurality of beveled gears 14. Bushings 15 mounted upon the casing 12 serve as bearings for the freely rotatable tubular members 16 positioned therein, which are driven by spur gears 17 meshing with the gears 14 hereinabove described. The tubular members 16 are connected with brushes generally designated by the reference character 18, by means to be hereinafter described, and bottles 20 carried in racks 21 are disposed in the vicinity of the brushes 18 whereby the brushes can be moved into contact with the bottles and out of contact therewith, as is common in devices of this character. The cleaning fluid is forced into the tank 12 through the pipe 12', and the pressure therein maintained so that, when the gear box is raised, the fluid will be forced outwardly through the channels 39a.
- 20 Reference is now made to Fig. 3 wherein a typical brush unit is illustrated and in which it will be noted that a hexagonal head 30 is mounted upon the threaded end portion 31 of the tubular member 16, the head being provided with an axially extending channel 32 leading to an inverted frusto-conical cavity formed in the up-

per head 30 substantially as shown. The outside top portion of the head 30 is threaded as designated by the reference character 34 to facilitate compression of the yielding annulus 35 received within the opening 33 which is pressed by a ring 36 held by the cap 37 engaging with the threads 34, substantially as shown. It will be obvious that both the upper and lower portions of the yielding annulus 35 are frusto-conical in shape and hence when a cap 37 is advanced upon the threads 34 of the head 30 the annulus 35 will exert compressive action radially toward its axis.

A tubular spindle 39 is axially positioned within the annulus and is provided with an opening 39a extending axially therethrough, the spindle being separated from the annulus by the split bushing 38 formed from a material such as resin impregnated sheet material or the like. The spindle is prevented from moving axially out of the annulus 35 by a ring 40 acting against a washer 41 which bears against the bottom end of the annulus 35, the ring 40 being secured on the spindle and in engagement with threads or by equivalent fastening means.

A sheath element 45, preferably formed of a relatively thin metallic substance and coated with a layer 46 of yielding material such as rubber or the like, is positioned around the spindle 39 extending substantially throughout the exposed length thereof as is shown in Fig. 3. A split collar 47, extending around the base portion of the sheath 45 and held in engagement therewith by the compression screw 48, is provided with a laterally extending arm 49 which, as will be seen from examination of Figs. 1 and 2, is provided with an opening to receive holding means 50 whereby the collars of adjoining cleaning units are held against rotation.

Referring again to Fig. 3 it will be noted that a radially extending opening 39b is provided in the spindle 39 communicating with the fluid passage 39a extending axially through the spindle, whereby cleaning fluid can serve to lubricate the interface of the spindle and the sheath. The end of the spindle is threaded, as designated by the reference character 51, to receive the threaded end portion of the brush ferrule 52 which, near the end thereof, is provided with a diametrically extending cross piece 53 upon which is mounted the brush stem 54 carrying the brush bristles, essentially as shown.

Referring now to Fig. 4 it will be seen that a sleeve 60 terminating in a stock collar 61 is carried upon a supporting head 62 disposed concentric with the spindle 39 and the sheath 45. A surface of the head 62 nearest the brush 18 is frusto-conical in shape as designated by the reference character 63 to serve as a guide for positioning the neck 20a of the bottle, generally designated by the reference character 20, whereby when the head is moved against the bottle neck, the neck end is guided against the member 64 positioned centrally within the head 62 thereby assuring alignment of the bottle neck with the sleeve 60. The supporting heads 62 are carried by a bar 66 which is slidably mounted on the frame 11, as is common in machines of this character.

In operation the shaft 13 is connected with

an appropriate power source and after brushes 18 have been positioned within the bottles 20, the cleaning fluid is forced through the channels within the spindles into the interior of the bottles, draining therefrom through the sleeves 60 into appropriate waste receptacles. Means (not shown) serve substantially automatically to move parts of the device into brushing and rest positions in predetermined sequence.

10 While, as hereinabove mentioned, it is preferred that the sheath 45 be formed from relatively thin metallic substance coated with a layer 46 of rubber or other yielding wear-resistant material, the sheath can be made from other substances such as plastics, laminated materials, metals, or the like, and under certain circumstances it will be apparent to those skilled in this art that the coating layer of rubber may be eliminated, depending upon the conditions of use.

20 As will be evident from the foregoing the purpose of the split bushing 38 is to prevent adherence of the yielding annulus 35 of rubber or like material to the spindle end. The bushing should not be made of thickness such as to interfere with firm holding of the spindle, nor should it be made too thin to serve its mentioned purpose. The formation of the annulus 35 in the manner described serves to permit the annulus functioning in conjunction with the head 30 and the cap 37 to hold the spindle end in a manner permitting yielding and adjustment of the spindle to conditions of use.

25 It is to be understood that this invention is capable of extended application and is not confined to the precise illustrated form nor described construction and, therefore, such changes and modifications may be made therein as do not affect the spirit of the invention nor exceed the scope of the appended claims.

30 Having thus described the present invention, what it is desired to secure by Letters Patent is:

35 1. A bottle cleaning machine, comprising, means for supporting a series of bottles in an inverted position, vertically movable heads having funnel shaped recesses to receive the necks of the bottles, vertically movable sheaths having a soft coating on their outer faces and adapted to pass through the heads into the bottles, vertically movable tubular spindles passing through the sheaths, brushes carried by the upper ends of the spindles, means for rotating the lower ends of the spindles, and means for supplying a fluid through said tubular spindles.

40 2. A bottle cleaning machine as set forth in claim 1, wherein the spindles have a loose fit in the sheaths, and wherein the sheaths are connected together below their upper ends by means adapted to hold them against rotation.

45 3. A bottle cleaning machine as set forth in claim 1, wherein the spindles have a loose fit in the sheaths, wherein the sheaths are connected together below their upper ends by means adapted to hold them against rotation, and wherein the spindles are provided near their upper ends 50 with radial openings communicating with the interior of the spindles to convey some of the fluid into the sheaths so as to lubricate the opposing faces of the spindles and sheaths.

FRANK E. FOWLER.
